UNITED STATES PATENT OFFICE.

GEORGE H. GERE, OF UTICA, NEW YORK.

CARBURETER.

No. 872,505.

Specification of Letters Patent.

Patented Dec. 3, 1907.

Application filed March 30, 1906. Serial No. 303,865.

To all whom it may concern:

Be it known that I, GEORGE H. GERE, a citizen of the United States, residing at Utica, in the county of Oneida and State of New York, have invented certain new and useful Improvements in Carbureters; and I do hereby declare the following to be a full, clear, and exact description of the invention, such as will enable others skilled in the art to 10 which it appertains to make and use the same.

My invention relates to improvements in carbureters; and its object is to provide improved means for controlling the flow of gasoline to the same, to provide improved means for vaporizing the gasoline and mixing it with the air, to provide improved means for controlling the flow of air therethrough, and to provide the device with various new and 20 useful features hereinafter more fully described and particularly pointed out in the claims, reference being had to the accompanying drawings, in which:

Figure 1. is a side elevation of a device embodying my invention with the tank shown in vertical section; Fig. 2. an enlarged view of my improved carbureter shown in vertical section; Fig. 3. a plan view of the same; Fig. 4. a modification of the same in vertical section; and, Fig. 5. a detail of a part of the gasoline pipe.

Like numbers refer to like parts in all of the figures.

1 represents the case of the device consisting of a horizontally extended hollow body provided with an air inlet opening 2 at one side and near one end, and an exit opening 3 provided with means adapted to connect the device with an internal combustion engine. 40 4 is a pipe to convey gasoline from the tank to a chamber located at the end of the case opposite the exit 3. In this chamber is a needle valve 5 to admit the flow of gasoline through a nozzle 5^a opening into the case close below the inlet valve and arranged substantially at right angles to the direction of the air current therein, whereby the gasoline is projected into and across the path of the air current and sprayed thereby. Such portion of the gasoline as escapes evaporation at once falls to the bottom of the case and collects in a depression 6 in the case.

7 is a valve to more or less close the air inlet opening 2. This valve is provided with 55 a side opening 7^a substantially at right angles to the air inlet opening of the valve.

Above the valve 5 and opposite said opening is a second needle valve 16, which discharges an auxiliary supply of gasoline through the opening 7^a whenever the valve 7 is wide open. This stream is also projected across the current of air and thus sprayed and more or less evaporated thereby before falling into the depression 6. A valve similar to the valve 7 is provided at the exit opening 3 to 60 adjust the same. These valves 7 and 8 are provided with levers 9 and 10 to simultaneously adjust the valves, the levers being connected by a rod 11 to which is pivotally attached a connection rod 12 extending to 70 any convenient operating means whereby the valves 7 and 8 are simultaneously operated to adjust the openings 2 and 3 and thus control the flow of air through the device.

To limit and regulate the flow of gasoline 75 to the carbureter, an air pipe 13 extends from near the top of the tank, and above the gasoline, down within the case 1 to a pre-determined line in the depression 6 and when the gasoline fills the depression up to the 80 end of this pipe, the air flowing into the tank 15 will be cut off thereby and the further flow of gasoline from the tank to the carbureter is prevented. The gasoline is thus constantly maintained at a pre-determined level in the carbureter. To adjust this pipe 13 vertically and thus change 85 the quantity of gasoline in the depression 6, said pipe is inserted in a sleeve 14 having a vertical screw adjustment in the case, whereby the lower end of the pipe may be adjusted relatively to the case by turning the said sleeve. To permit this adjustment, the pipe 4 is provided with a series of elbows and nipples 4^a whereby the distance between the 90 tank and the carbureter may be varied without affecting the operation of the pipe 4.

To fill the tank 15, and to maintain the same air tight, to enable the air pipe to regulate the flow, a plug 17 is inserted in a collar 18 mounted on the tank and this plug is surrounded by packing 19 engaged by the flange of the plug, and to further insure a tight joint, the upper end of the plug is threaded as at 21, and a cap 20 covers this plug, and has an inner thread engaging the plug and is held down thereby with its rim upon the packing, thus securing a double packed joint to keep out the air.

In the modified construction shown in the 110 Fig. 4., both pipes 13 and 4 are inserted in the vertically adjustable sleeve 14; the valve

5 is placed in the plug, and the nozzle 5^b extends vertically therefrom, and discharges the gasoline vertically across the horizontal current of air passing over the gasoline in the depression 6. This modification simplifies the structure and dispenses with the gasoline valve 16 and the extension mechanism 4^a and serves all purposes under some circumstances, as for instance with marine engines working normally at full capacity.

What I claim is:

1. The combination of a case having a depression in the bottom thereof, means for admitting a current of air to the case, means 15 for removing a combustible mixture from the case, a vertically adjustable sleeve in the case, a nozzle in the case, an air tight tank above the case, a pipe connecting the bottom of the tank and the nozzle and having means 20 for longitudinal expansion, a pipe extending from the depression to the upper part of the tank and vertically adjusted relative to the case by means of the sleeve.
2. The combination of a case, an air inlet 25 valve in the case and having openings for air and for gasoline, a gasoline valve outside the air valve, means for supplying gasoline to both of said valves, means for remov-

ing a combustible mixture from the case, and means for closing the gasoline opening of the air valve except when the air opening of the same is nearly or quite wide open.

3. The combination of a case, an air inlet valve having a side opening to admit gasoline only when said air valve is nearly or 35 quite open, a nozzle below said valve, means for supplying gasoline to said valve and nozzle, and means for removing a combustible mixture from the case.

4. The combination of a case, an air valve 40 near one end of the case, and having a side opening to admit gasoline only when said air valve is nearly or quite wide open, a nozzle below said air valve, an air tight tank, a pipe connecting the lower part of the tank with the valve and nozzle, a pipe connecting the lower part of the case and the upper part of the tank, and means for removing a combustible mixture from the case.

In testimony whereof I affix my signature 50 in presence of two witnesses.

GEORGE H. GERE.
